UNITED STATES PATENT OFFICE.

JOHN OWEN FORD, OF JACKSONVILLE, TEXAS.

COMBINED DOOR AND GATE STOP.

1,108,731.

Specification of Letters Patent. Patented Aug. 25, 1914.

Application filed April 16, 1914. Serial No. 832,303.

To all whom it may concern:

Be it known that I, JOHN O. FORD, a citizen of the United States, resident of Jacksonville, in the county of Cherokee and State of Texas, have made a certain new and useful Invention in Combined Door and Gate Stops; and I declare the following to be a full, clear, and exact description of the same, such as will enable others skilled in the art to which it appertains to make and use the invention, reference being had to the accompanying drawings, and to letters or figures or reference marked thereon, which form a part of this specification.

Figure 1 is a side view of the invention as applied, the bearing foot being shown in raised position in dotted lines. Fig. 2 is a front view of the invention, with the bearing foot lowered. Fig. 3 is a similar view with the bearing foot raised. Fig. 4 is a section on the line 4—4, Fig. 3.

The object of the invention is to provide an improved stop for doors and gates, and consists in the novel construction and combination of parts, as hereinafter set forth.

In the accompanying drawings, illustrating the invention, the numeral 2, indicates the bottom portion of a door or gate, and 3, the stop which is designed to be secured thereto near its outer free marginal portion.

The stop 3, consists of a holder 4, and a bearing foot 5, which is carried by the holder. A rubber tip 6, is usually attached to the foot.

The holder 4, is made of sheet metal and consists of side walls 7, which are substantially parallel to each other, and a back wall 8, to which the side walls are connected. The holder is open in front and may be provided with lateral strengthening flanges 9, projecting outward from the front and bottom of each side wall. The back wall 8, is provided with perforations for the passage of fastening screws as at 10, these being designed to secure the holder to the door or gate.

The bearing foot 5, is designed to be reversible and is pivoted between the side walls by means of a pivot pin at 12, in the lower portion of the holder. The bearing foot may be made of wood, porcelain, glass or other material. In the drawing it is shown as made of metal, preferably, a piece of sheet metal bent to provide side walls 14, through which the pivot pin passes. This bearing foot is designed to be long enough

to project below the lower end of the holder sufficiently to engage the floor when the foot extends downward and forward in oblique position, in such wise as to form a brace. 60 This bearing foot is designed to have a slight taper from its lower or free end toward its upper or pivotal portion, this taper being sufficient to provide for frictional engagement of its sides with the side walls of the holder, when the foot is turned or revolved upward on the pivot. When in this up-turned position, the bearing foot is designed to extend upward and backward in oblique position, so that its center of gravity 70 will be in rear of the pivot, and in this way additional means is provided to keep the bearing foot from falling. To this end the pivot is located well forward of the back of the holder, and in such wise that an interval, 75 as at 15, is provided between the pivot pin and the back of the holder, when the bearing foot is in raised position. When the bearing foot is dropped, its upper end is designed to approach the back of the holder more 80 closely. The sides of this pivoted foot are designed to be provided with laterally projecting studs or lugs 16, which are intended to facilitate moving the same to raise it to position of rest in the holder, or to disengage it from between the side walls of the holder so that it will fall to engage the floor.

The rubber tip 6, is secured to the free end of the bearing foot, and in the drawing is shown clamped between the side walls 14. 90 When the bearing foot is made of wood or porcelain, the rubber tip may be recessed for application to its end.

The metal structure shown is particularly suitable for out door use, as upon a gate, the bearing foot having greater strength, weight and durability than when made of the other materials referred to. Sometimes, as in the case of a hanging gate, it is of advantage to use two of these stops, one on each side of the gate. When both of these stops are brought to work, the bearing foot of each being dropped, the gate is held from moving forward or backward. Another advantage is that if the gate be lifted slightly, these stop bearings will take firm engagement with the ground, so as to support the gate and to a great extent relieve the hinges of its weight.

I claim:

1. A door stop consisting of a holder having a back portion for attachment to the

door, and side walls projecting forward therefrom, a pivot pin in the lower part of the holder, and an oblique lengthwise tapering bearing foot pivoted by its narrow end 5 on said pin between said side walls, and adapted to engage the side walls of said holder by the sides of its broader end when upturned to oblique position, said foot having laterally projecting lugs.

13. 2. A door stop consisting of a bent sheet metal holder having a back portion and side walls projecting forward therefrom, a pivot pin in the lower part of the holder, and a bent sheet metal bearing foot having sides

tapering lengthwise toward each other and 15 engaging the pivot pin by its narrow end, said bearing foot being reversible from oblique working position to an oblique upturned position of engagement by the sides of its broader end with the side walls of 20 said holder.

In testimony whereof I affix my signature, in presence of two witnesses.

JOHN OWEN FORD.
